UNITED STATES PATENT OFFICE.

ERIC A. STARKE, OF ALAMEDA, CALIFORNIA.

METHOD OF RENDERING ASPHALTIC OILS MORE LIMPID.

SPECIFICATION forming part of Letters Patent No. 781,240, dated January 31, 1905.

Application filed August 17, 1903. Serial No. 169,744.

To all whom it may concern:

Be it known that I, ERIC A. STARKE, a citizen of the United States, residing at Alameda, in the county of Alameda and State of California, have invented new and useful Improvements in Methods of Rendering Asphaltic Oils More Limpid, of which the following is a specification.

My invention relates to a method for reducing the viscosity of heavy crude mineral oils, and particularly oils of asphaltum base.

The sticky and immobile quality of the heavier asphaltic oils renders it difficult to transport them through pipe-lines or to use them to advantage for fuel purposes. The ordinary method of heating the oil to cause it to flow more readily is only temporary in effect, and as soon as the oil cools it returns to its normal sluggish viscous state.

The object of my invention is to so treat the oil that while retaining, essentially, all its original constituents it will be rendered permanently limpid.

In the practice of my invention I proceed as follows: I subject the heavy crude oils to a partial distillation by distilling off a certain quantity therefrom and then reunite the distillate with the undistilled residuum or "still-bottom" and thoroughly mixing the two. This is the finished product. The amount of distillate that is to be taken off from a still charge depends wholly upon the limpidity of the product desired, the greater the desired fluidity the larger the amount of distillate. In my experiments I have found that about one-half of the still charge as distillate is sufficient. If distillation proceeds much beyond one-half, the residuum of the charge or "still-bottom," as it is called, becomes converted into coke. It is desired for obvious reasons to discontinue distillation short of coking or before any considerable carbonization takes place. The small amount of carbon that may be formed is so finely divided as to be imperceptible.

The process is essentially one of dry distillation. If steam, for example, were admit-

ted to the charge during distillation no permanent change in the final product would result—that is, the original viscous character of the oil would remain; but when the oil is subjected to dry heat at a temperature ranging from 500° to 650° Fahrenheit a molecular disturbance or "cracking" takes place, so that when the subsequent admixture of the distillate and still-bottom occurs the resulting product is a liquid of approximately the same bulk as the original body, but of lighter and more limpid quality, which will flow readily at ordinary temperatures.

The figure represents an apparatus suitable for carrying out my process.

A is a retort of ordinary construction. The crude oil is admitted at 2. The distillate is thrown over to the condenser 3 through a pipe 4, the condensed product being collected in a tank 5. When distillation has proceeded to a certain point, the still-bottom is discharged through pipe 6 into tank 5 and thoroughly mixed with the distillate already therein. The still-bottom is suitably cooled during its passage from the retort to the tank.

Having thus described my invention, what I claim, and desire to secure by Letters Patent, is—

1. The process of rendering heavy mineral oils more liquid which consists in subjecting the oil to a partial distillation at a temperature ranging from 500° to 650° Fahrenheit and reuniting the distillate and residuum and mixing the mass thoroughly.

2. The process of rendering heavy oils of asphaltum base more liquid, which consists in subjecting the oil to dry distillation, discontinuing distillation short of coking, and reuniting the distillate and "still-bottom."

3. The process of rendering heavy mineral oils more limpid which consists in subjecting the oil to destructive distillation sufficient to crack the "still-bottom," collecting the distillate and then reuniting the cracked still-bottom and distillate.

4. The process of rendering heavy mineral oils more limpid which consists in subjecting

the oil to a partial distillation at such temperature as to effect a separation of the more volatile products from the "still-bottom," continuing the distillation to such time and at 5 such a temperature as to crack the still-bottom and reuniting the distillate and cracked residuum.

In testimony whereof I have hereunto set my hand in presence of two subscribing witnesses.

ERIC A. STARKE.
